MONOVALVE CYLINDER HEAD CONSTRUCTION

Walker M. Pate, New Orleans, La., assignor of
one-half to Thomas F. Boyle, New Orleans,
La.

Application January 11, 1937, Serial No. 120,082

9 Claims. (Cl. 123—79)

This invention appertains to new and useful improvements in the art of internal combustion engines and more particularly to a novel cylinder head construction of the single poppet valve exhaust and air admission type.

In this type of exhaust and air admission control, a single valve, usually of the poppet type, is employed for permitting exhaust of the products of combustion on the exhaust stroke of the piston, and also admission of air during the suction stroke of the piston.

Numerous patents have been issued along this line with the aim in view of utilizing a single passageway having an intermediate portion communicating with the combustion chamber of the cylinder at the port of the single valve, to the end that air will be supplied to the combustion chamber from one end of the passageway, while the products of combustion will be expelled 20 through the valve port toward the opposite end of the passageway.

The attempts heretofore to control the admission of air and to exhaust burned gases in a mono-valve type engine, with a single passageway for air admission and exhaust, have been met with only mediocre success, due to the so far unsolved problem of keeping the exhaust gases from exhausting into the air supply side of the single passageway, without the employment of 30 supplemental valve mechanism for this specific purpose.

The principal object of this invention is to provide a single valve cylinder head construction wherein the single air admission and exhaust passageway is constructed in such a manner as to preclude the exhausting of the products of combustion into the air admission side of the passageway, and this without the employment of any movable mechanical parts; and further- 40 more to relate the air admission side of the passageway with the exhaust side of the passageway in such a manner as to cause a definite directional movement of the air supply from the air supply side of the passageway to the valve port, when the valve is in open position, and into the exhaust side of the passageway, only when the valve is in closed position to clear and cool the exhaust side of the passageway.

50 Various other important objects and advantages of the invention will become apparent to the reader of the following specification.

In the drawing:—

Figure 1 represents a fragmentary vertical sec- 55 tional view through the upper portion of an in-

ternal combustion engine constructed in accordance with the present invention.

Figure 2 is a fragmentary vertical sectional view taken substantially on the line 2—2 of Figure 1.

Referring to the drawing wherein like numerals designate like parts, it can be seen that numeral 5 represents the usual cylinder block having the bore 6 therein receiving the piston 7.

Numeral 8 denotes the novel cylinder head construction in which the combustion chamber 9 is located. It will be observed that this combustion chamber 9 is of frustro-conical shape having the poppet valve seat 10 at its upper end. As this is a mono-valve type cylinder head construction the 15 port at the top of the combustion chamber 9 is the only communication between the combustion chamber and the air admission and exhaust passageway construction generally referred to by reference characters 11—12. An air supply tub- 20 ing 13 connects to the inlet end of the air admission side 11 of the passageway, while the exhaust tubing or conduit 14 connects with the outlet end of the exhaust side 12 of the passageway.

It can be seen in Figure 1 that the air admission side 11 of the passageway is substantially on a horizontal plane, with the inlet end *a* located a substantial distance below the outlet end *b* of the exhaust side 12. Furthermore, it can be seen that the exhaust side of the passageway is 30 substantially in the form of a curved elbow having the inner end of the air admission side 11 communicating with its lower end just above the valve port of the combustion chamber 9.

To effect an arcuate sweep of the air through 35 the air supply side 11 of the passageway, the top portion *c* of the air supply side of the conduit is curved downwardly toward the combustion chamber port and to maintain the cross sectional area of this portion 11 of the passageway 40 throughout the length of this portion, the air admission portion 11 of the passageway gradually increases in width while decreasing in depth until it merges with the ovate orifice 15 at the inner end of the air admission side 11, that is, where 45 the air admission side of the passageway merges with the lower end of the exhaust side 12 of the passageway. This affords a lip 11a which serves to deflect air across the adjacent end of the exhaust tube 12 and directly into the port 10. 50 However, it will be noted that the specific purpose in having the combustion chamber 9 of frustro-conical shape is so that the exhausting gases will be directed exclusively into the exhaust side 12 of the conduit. With this in mind, it can 55

be seen that the orifice 15 is located in the offset wall portion *d* of the lower end of the exhaust side 12 of the passageway so that as the burned gases are exhausting they will shoot upwardly through the exhaust side 12 of the passageway without entering the side 11. Immediately on the intake stroke of the piston 7 air in passing through the side 11 of the passageway will be guided in such a manner as to describe a slight 10 arc which will find its inner end entering the port of the combustion chamber 9.

When the valve 16 is in closed position of course air passing through the side 11 of the passageway will be shunted upwardly through 15 the side 12 of the passageway for the purpose of clearing the passageway and cooling the valve.

Figure 1 also shows the usual stem 17 of the valve 16 which operates through the guide 18, which guide is mounted in the guide boss 19. 20 The upper end of the stem 17 is engaged by the usual valve rocker 20 and a spring 21 is provided on the stem for holding the valve 16 in seated position.

Numeral 22 represents the usual fuel injector 25 for the combustion chamber 9.

It will furthermore be observed that the products of combustion in escaping through the passageway 12 will draw air from conduit 13 into the said passageway to aid in the cooling of the 30 exhaust gases. Moreover, the flow of air is constant, passing through the entire passageway when the valve is closed, incidentally cooling the valve, and passing through to the combustion chamber when the valve is open.

35 While the foregoing specification sets forth the invention in specific terms, it is to be understood that numerous changes in the shape, size and material may be resorted to without departing from the spirit and scope of the invention as 40 claimed hereinafter.

Having described the invention what is claimed as new is:—

1. In a mono-valve cylinder head construction, 45 a combustion chamber having a valved port, an exhaust passageway extending coaxially from the port and delivering the exhaust to an outlet adjacent that part of the cylinder head remote from the cylinder, and an air supply passageway opening into the exhaust passageway adjacent the 50 port, said air supply passageway being constructed and disposed to deliver air directly into the port.

2. In a mono-valve cylinder head construction, 55 a combustion chamber having a valved port, an exhaust passageway extending coaxially from the port and delivering the exhaust to an outlet adjacent that part of the cylinder head remote from the cylinder, and an air supply passageway opening into the exhaust passageway adjacent the 60 port, said air supply passageway being constructed and disposed to deliver air directly into the port, the port end of the exhaust passageway being provided with a lateral pocket into which the air supply conduit opens.

65 3. In a mono-valve cylinder head construction, a combustion chamber having a valved port, an exhaust passageway extending coaxially from the port and delivering the exhaust to an outlet adjacent that part of the cylinder head remote from the cylinder, and an air supply passageway opening 70 into the exhaust passageway adjacent the port, said air supply passageway being constructed and disposed to deliver air directly into the port, said combustion chamber being of upwardly tapering construction for delivering the

burned products of combustion well into the exhaust passageway and beyond the adjacent end of the air supply passageway.

4. In a mono-valve cylinder head construction, 5 a combustion chamber having a valved port, an exhaust passageway extending coaxially from the port and delivering the exhaust to an outlet adjacent that part of the cylinder head remote from the cylinder, and an air supply passageway opening into the exhaust passageway adjacent the 10 port, said air supply passageway being constructed and disposed to deliver air directly into the port, the port end of the exhaust passageway being provided with a lateral pocket into which the air supply conduit opens, said combustion chamber being of upwardly tapering construction so as to guide the exhaust gases well into the exhaust passageway so as to avoid the adjacent end of the air supply passageway.

5. In a mono-valve cylinder head construction, 20 a combustion chamber having a port, an arcuate air supply passageway constructed adjacent and arranged to deliver a flow of air immediately into the port, a valve for the port, and an exhaust passageway into which the air passageway opens, 25 said exhaust passageway extending coaxially away from the said port, and delivering the exhaust to an outlet adjacent that part of the cylinder head remote from the cylinder.

6. In a mono-valve cylinder head construction, 30 a pair of arcuate-shaped passageways, a combustion chamber having a valved port with which the passageways communicate, said passageways merging together with their meeting point describing an air deflector offset laterally from the 35 port for deflecting air directly into said port from one of said passageways.

7. In a mono-valve cylinder head construction comprising a combustion chamber having a port with a valve for said port, an exhaust passageway 40 having its inner end coaxial with the valve stem and enveloping the said port, an air supply conduit opening into the said exhaust passageway adjacent the port in laterally offset relation to the axis of the said port.

8. In a mono-valve cylinder head construction comprising a combustion chamber having a port with a valve for said port, an exhaust passageway having its inner end coaxial with the valve stem and enveloping the said port, an air supply 50 conduit opening into the said exhaust passageway adjacent the port in laterally offset relation to the axis of the said port, the top portion of the air supply passageway being curved longitudinally and converging with the bottom portion of the passageway to cause the supply of air to sweep into the lower portion of the exhaust passageway and directly into the said port.

9. In a mono-valve cylinder head construction comprising a combustion chamber having a port 60 with a valve for said port, an exhaust passageway having its inner end coaxial with the valve stem and enveloping the said port, an air supply conduit opening into the said exhaust passageway adjacent the port in laterally offset relation to the axis of the said port, the top portion of the air supply passageway being curved longitudinally and converging with the bottom portion of the passageway to cause the supply of air to sweep into the lower portion of the exhaust 65 passageway and directly into the said port, said air supply passageway gradually increasing in width inwardly so as to maintain a constant cross sectional area throughout its length.
